US00D865706S

(12) **United States Design Patent** (10) **Patent No.:** **US D865,706 S**
Li et al. (45) **Date of Patent:** **** Nov. 5, 2019**

(54) **HEADPHONE**

(71) Applicant: **Shenzhen Coolhear Information Technology Co., Ltd.**, Shenzhen, Guangdong (CN)

(72) Inventors: **Bin Li**, Guangdong (CN); **Chuanbo Wang**, Guangdong (CN); **Mengran You**, Guangdong (CN)

(73) Assignee: **Shenzhen Coolhear Information Technology Co., Ltd.**, Shenzhen (CN)

(**) Term: **15 Years**

(21) Appl. No.: **29/626,482**

(22) Filed: **Nov. 17, 2017**

(30) **Foreign Application Priority Data**

Sep. 21, 2017 (CN) 2017 3 0450164

(51) **LOC (12) Cl.** **14-01**

(52) **U.S. Cl.**

USPC **D14/205**

(57) **CLAIM**

The ornamental design for a headphone, as shown and described.

DESCRIPTION

FIG. 1 is a front elevational view of a headphone showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof; and,

FIG. 8 is a second perspective view thereof.

The broken lines depict environment that forms no part of the claimed design.

1 Claim, 8 Drawing Sheets
